UNITED STATES PATENT OFFICE.

LOUIS B. GOLDBERG AND NATHAN GOLDBERG, OF DENVER, COLORADO.

AUTOMATIC HASP-LATCH.

1,322,105.

Specification of Letters Patent.

Patented Nov. 18, 1919.

Application filed August 23, 1918. Serial No. 251,096.

To all whom it may concern:
Be it known that we, LOUIS B. GOLDBERG and NATHAN GOLDBERG, citizens of the United States, residing at the city and county of Denver and State of Colorado, have invented certain new and useful Improvements in Automatic Hasp-Latches; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to hasps and constitutes a latch or retainer to automatically engage a stud or like member projecting through the eye in the hasp to retain the hasp in operative position.

The invention is designed particularly for use on shipping cases for motion picture films, and the object is the provision of a device which will positively and automatically secure the hasp when it is moved to closed position, without the use of a separate member such as a padlock or snaphook. Commonly the film case is closed merely by passing the eye of the hasp over a pivoted headed stud and then turning the head at an angle. But since no further means is used, the head frequently will turn back through handling of the case until the head is in alignment with the eye, so that sudden movement or jolting of the case will cause the hasp to fly off the stud, with the result that the lid swings open and the film-roll falls out.

It is very desirable therefore to have a simple and preferably automatic means on the hasp that will secure the hasp against accidental movement from the stud. This invention provides such a means which assumes its operative position as soon as the hasp is positioned, and may be readily withdrawn to release the hasp. Briefly it comprises a plate slidable on the hasp and spring pressed to cause it to assume operative position, the forward end of the plate being adapted to engage the head of a stud. The stud has a sloping portion to guide and retract the slide as the hasp moves to operative position and has a lower shoulder to engage and retain the sliding plate. In the drawings:

Figure 1 is an elevation of a shipping case with the invention applied thereto.

Fig. 2 is a longitudinal section taken on the line 2-2 of Fig. 1 showing the hasp, the latch, the stud and a part of the casing on an enlarged scale.

Fig. 3 is a plan as indicated by line 3-3 of Fig. 2 but with the head of the stud omitted.

Fig. 4 is a cross section on the line 4-4 of Fig. 3.

Fig. 5 is a longitudinal section on line 5-5 of Fig. 3.

Fig. 6 is a plan similar to that of Fig. 3 but showing the latch retracted.

The shipping case A has a pivotally mounted headed stud 10 thereon and the hinged lid B of the case has a hasp 20 hinged thereto, the hasp carrying a slidably mounted spring-controlled latch plate 30.

The stud 10, pivotally mounted in the case at 11, has a head 12, the upper portion 13 of which is rounded or sloped while the under portion is in the form of a shoulder 14. An aperture 15 for the reception of the bail of a padlock may be provided if desired.

The hasp 20 has the usual longitudinally extending eye 21 to receive the stud 10. The hasp is provided at its forward end with a pair of struck up lugs 22 to limit the forward motion of the latch plate 30, and at an intermediate point with a pair of lugs 23 to engage the ends of the springs 31 for compression of the same. The springs 31 are mounted in channels in the under face of the latch plate extending longitudinally thereof, corresponding upstanding ribs 33 being formed on the outer face of the plate. These ribs, when the latch is in operative position, extend along both sides of the eye 21 of the hasp. The forward end of the latch has a slot 34 therein so that the sides of the latch plate adjacent the slot 34 will pass along the sides of the stud when moving into operative position. At the inner end of the slot the latch plate is rolled up slightly at 35 to provide a surface which will ride smoothly on the rounded portion 13 of the stud head 12. The outer ends of the channels 32 are closed at 36 to retain the springs 31. To retract the latch plate manually to release it from the stud an upstanding finger piece 37 is provided at the rear thereof. The edges of the plate are bent around the sides of the hasp to form guides 38 to retain the plate on the hasp.

In operation the stud 10 is positioned to enter the eye 21 and the hasp is then swung

down to pass over the stud, whereupon the rolled edge 35 engages the rounded sloping face 13 with the result that, as the hasp continues to move down, the latch plate is retracted against the tension of the springs 31 until the edge 35 passes below the shoulder 14. The latch plate is then projected forwardly under the shoulder 14 by the springs, thus securing the hasp in position 10 until the latch plate is manually withdrawn as through the medium of the finger piece 37. The ribs 33 will limit the rotation of the stud head 12 by engagement therewith, so that it will not have to be rotated through 15 a large arc to release the hasp. The stud might be fixed if it were not for the fact that it is very desirable to use the stud already provided on a shipping case, and also for the fact that a rotary stud will also 20 be of some value in case the spring pressed latch plate is rendered inoperative by accident or otherwise.

We claim:

1. The combination with a pivoted headed 25 stud and a hasp having an eye therein for the reception of the stud, of a spring actuated plate slideable on the outer face of the hasp into position to engage the stud to prevent withdrawal thereof from the eye, 30 said plate having ribs on the outer face thereof forming corresponding channels in its under face, said ribs lying on opposite sides of the eye when the plate is in operative position to limit rotation of the head, 35 and springs in the channels to urge the plate into and retain it in operative position.

2. The combination with a headed stud and a hasp having an eye therein for the reception of the stud of a spring-actuated plate, slideable on the outer face of the hasp into position to engage the stud to prevent withdrawal thereof from the eye, said plate having ribs on the outer face thereof forming corresponding channels in its under face, said ribs lying on opposite sides of 40 the eye when the plate is in operating position to limit rotation of the head, and springs in the channels to urge the plate into and retain it in operative position, the side portions of said plate being bent about 45 the sides of said hasp and forming grooves in which the hasp is held and by which the sliding of the plate on the hasp is guided.

3. The combination with a headed stud 55 and a hasp, having an eye therein for the reception of the stud, of a spring-actuated plate slideable on the outer face of the hasp to engage the stud to prevent withdrawal from the eye, said plate having a rib on the 60 outer face thereof forming a corresponding channel in its under face and a spring in the channel to urge the plate into and retain it in operative position, the side portions of the said plate being bent about the 65 sides of said hasp and forming grooves in which the hasp is held and by which the sliding plate is guided.

In testimony whereof we affix our signatures.

LOUIS B. GOLDBERG.
NATHAN GOLDBERG,
